UNITED STATES PATENT OFFICE

137,605

DESIGN FOR A SCAFFOLD UNIT

Leo A. Reiner, Detroit, Mich.

Application February 17, 1944, Serial No. 112,618

Term of patent 14 years

(Cl. D54—1)

To all whom it may concern:

Be it known that I, Leo A. Reiner, a citizen of the United States, residing at Detroit, in the county of Wayne and State of Michigan, have invented a new, original, and ornamental Design for a Scaffold Unit, of which the following is a specification, reference being had therein to the accompanying drawing, forming part thereof.

Figure 1 is a front elevational view of a scaffold unit showing my new design;

Figure 2 is a top elevational view of the same; and

Figure 3 is a side elevational view of the same.

What I claim is:

The ornamental design for a scaffold unit, as shown.

LEO A. REINER.
